(57) **CLAIM**

The ornamental design for a vehicle wheel, as shown and described.

DESCRIPTION

FIG. 1 is a front view of a vehicle's wheel;

FIG. 2 is a left view of the vehicle's wheel;

FIG. 3 is a perspective view of the vehicle's wheel; and,

FIG. 4 is a back view of the vehicle's wheel.

The right view is a mirror image of the left view.
